ANTENNA SYSTEM

George H. Brown, Princeton, N. J., assignor to
Radio Corporation of America, a corporation of
Delaware

Application March 31, 1943, Serial No. 481,218

7 Claims. (Cl. 250—11)

1

This invention relates to directive antennas and more particularly to antennas for providing alternately or sequentially overlapping directive patterns. Such antennas are generally applicable to radio aircraft locators, radio direction finders, object detectors and the like. Directive antenna systems for ultra high frequencies frequently include a parabolic reflector with one or more radiator elements disposed at or near the focal point. The directive characteristic of the reflector is superimposed upon the field pattern of the radiator, providing substantially a single narrow pattern lobe. The axis of this lobe may be altered with respect to the axis of the reflector by moving the radiator system off center, or by providing an unsymmetrical secondary reflector or director adjacent the radiator and rotating or oscillating said secondary member.

It is the principal object of the present invention to provide an improved system of the above described type having no moving parts and capable of providing either two or four overlapping directive lobes.

Another object is to provide an antenna system of the above described type in which the necessary switching may be done at any convenient point in the feed system between the antenna and associated radio apparatus.

A further object is to provide a structure of the above described type which is mechanically strong.

These and other objects will become apparent to those skilled in the art upon consideration of the following description with reference to the accompanying drawing, of which Fig. 1 is a perspective view of a radiator structure according to the instant invention, Fig. 2 is a schematic diagram of the structure of Fig. 1 and the associated transmission line circuits, and Fig. 3 is a schematic diagram of a portion of the system of Fig. 1. Similar reference characters indicate similar elements in the drawing.

Referring to Figs. 1 and 2 a coaxial transmission line 1 has its inner conductor connected to a radiator 3 substantially $\frac{1}{4}$ wave length long. Four radiator elements 5, 7, 9 and 11 are provided at the end of the outer conductor of the line 1 and extend radially therefrom along two lines at right angles to each other. Each of the elements 5, 7, 9 and 11 comprise an inner conductor 13, which is connected to the outer conductor of the line 1, and an outer conductor connected to the inner conductor at the outer end thereof by a plug 15. The outer conductors are made slightly shorter than the inner conductors to avoid contact

2

with the line 1. Each of the radiator elements 5, 7, 9 and 11 is approximately $\frac{1}{4}$ wave length long. Four coaxial lines 17, 19, 21 and 23 surround the line 1 with their outer conductors connected to the outer conductor of the line 1. The inner conductors of the lines 17, 19, 21 and 23 are connected to the outer conductors of the radiator elements 5, 7, 9 and 11 respectively. The above described structure is positioned in a parabolic reflector, not shown. The focal point of the reflector lies approximately in the plane of the radiator elements 5, 7, 9 and 11.

The lines 17 and 21 are connected together at a point 25 which is one-half wavelength further from the radiator 5 than from the radiator 9, so that voltage applied to the point 25 will excite the elements 5 and 9 180 degrees out of phase. The total length of the line between the radiators 5 and 9 is one and one-half wavelengths, or any odd number of half wavelengths. A transmission line 27 is connected to the point 25 and through a line section 29 one-half wavelength long to a line 31. A switch 33 is connected across the section 29. The radiator elements 7 and 11 are similarly connected to a junction point 35, a line 37 one-half wave section 39, a line 41 and a switch 43. The lines 31 and 41 are connected to a double throw switch 45 which is connected to the line 1 and through a line 47 to a radio device, not shown.

A power division network may be provided in the connections between the line 47, the line 1 and the switch 45 if necessary to provide the proper ratio between the energizations of the element 3 and the radiators 5, 7, 9 and 11. The total length of the line from the switch 45 to each of the elements 5, 7, 9 and 11 is an odd number of quarter wavelengths. The switches 33, 43 and 45 may comprise rotatable variable capacitor means connected with resonant line sections or any other well known type of radio frequency circuit making and breaking devices. These switches may be mechanically ganged together for sequential operation by means of an electric motor 46 or the like.

The operation is as follows:

Assuming the antenna is to be used for transmission, the radiator 3 is constantly energized through lines 1 and 47. The switch 45 alternately connects the lines 31 and 41, energizing the respective dipoles 5, 9, and 7, 11. When the line 31 is connected to the line 47, the open circuit presented at the lower end of the line 41 is transformed to a short circuit at the upper ends 55 of the lines 19 and 23, effectively grounding the

outer conductors of the members 7 and 11. The radiators 5 and 9 are similarly grounded when the radiators 7 and 11 are energized. When the switch 33 is open the total length of the line between the switch 45 and the radiators 5 and 9 is one-half wave longer than when the switch 33 is closed. Thus by opening and closing the switch 33, the polarity of the dipole 5, 9 is reversed. Similarly when the lines 41 and 47 are connected together by the switch 45, operation of the switch 43 reverses the polarity of the dipole 7, 11.

The radiation pattern of the radiator 3, neglecting the effect of the reflector is approximately the shape of a torus with an inner radius of zero, maximum energy being radiated in all directions at right angles to the axis of the radiator 3.

The reflector 24 modifies the pattern by concentrating it in a forward direction to form a relatively narrow hollow conical beam, with maximum radiation in all directions at a predetermined small angle to the axis. This pattern is substantially the same whether one pair or the other of the elements 5, 7, 9 and 11 is grounded. When the switch 45 connects the line 31 and the switch 33 is closed, current flows in the radiator elements 5, 9, and 3 as indicated by the solid arrow in Fig. 2. The current through the elements 5 and 9 provides a toroidal radiation pattern with the axis of minimum radiation along the axis 5, 9. The reflector 24 modifies this pattern to form a single narrow lobe with its maximum intensity along the axis of the element 13.

At a point R in space ahead of and to the right of the array, the electric field vector produced by the element 3 is at right angles to the line between the antenna system and the point R, and is directed toward the center. The electric field vector produced by the dipole 5, 9 at point R is also at right angles to the radial line CR, but extends in the opposite direction. Thus the fields tend to cancel.

At a point L to the left of the axis of the radiator 3 the field vector produced by the radiator 3 is again at right angles to the line from the antenna to the point L and directed inwardly. The field vector at L produced by the dipole 5, 9 is also at right angles to the line CL but extends in the same direction as that produced by the element 3 at point L. Thus the total radiation pattern is asymmetrical, having a point of maximum intensity to the left of the axis of the radiator 3.

If the switch 33 (Fig. 2) is now opened, the polarity of the dipole 5, 9 is reversed, producing field vectors at points L and R as indicated by the dash arrows. The fields are now added at the points to the right of the axis of the radiator 3 and subtracted at points to the left of radiator 3.

Thus by operating the switch 33 two overlapping radiation lobes are produced alternately by the elements 35 and 9. The axis of maximum radiation of two lobes lie in the plane defined by the elements 3, 5, and 9. The operation of the radiators 7 and 11, when the switch 45 is thrown to connect lines 41 and 47 is identical with the above described operation. However, the axis of maximum radiation will now lie in the plane determined by the elements 3, 7 and 11. By operating the switches 33, 43 and 45 in the proper sequence, four overlapping directive patterns are provided

in any desired order. A fifth lobe, centered on the axis of the array, may be provided by opening both switches on the array 33 and 43, deenergizing the radiators 5, 7, 9 and 11.

5 I claim as my invention:

1. An antenna system comprising four coplanar radiators extending radially from a common center, a fifth radiator extending from said center at right angles to the plane of said coplanar radiator, 10 means for energizing said fifth radiator constantly and means for selectively energizing collinear pairs of said coplanar radiators.

2. An antenna system including two pairs of collinear radiators lying in a common plane, said 15 pairs being disposed at an angle to each other, two concentric transmission lines each connected between the adjacent ends of the radiators of one of said pairs, two branch concentric lines each connected to one of said first mentioned lines at a point one-quarter wave length distant from the midpoint thereof, each of said branch lines including a one-half wave line section and means for selectively including and removing said section from the circuit thereof, a main transmission line, 20 means for connecting said main transmission line selectively to one of said branch lines, and a radiator element disposed at right angles to the plane of said coplanar elements and connected to said main transmission line.

30 3. The invention as set forth in claim 2 wherein each of said two coplanar radiator elements comprises a concentric line section substantially one-quarter wave length long and short-circuited at its outer end and with its inner conductor to the end of the outer conductor of said main transmission line.

40 4. The invention as set forth in claim 2 including a substantially parabolic reflector arranged with its focal plane lying substantially in the plane of said coplanar radiators.

50 5. An antenna system comprising pairs of collinear radiator elements lying in a common plane, each of said elements comprising a coaxial line section substantially one-quarter wave length long with its inner conductor connected to a grounded 45 supporting member at one end and to its outer conductor at the other end, two concentric lines each connected between the outer conductors of a respective pair of radiators, each of said concentric lines being substantially an odd number of half wave lengths long, two branch lines, one connected to each of said first mentioned lines at a point one-half wave length further from one radiator element than from the other radiator element of the respective pair, a fifth radiator element extending at right angles to two of said coplanar elements and connected to a main transmission line, and means for selectively connecting said branch lines to said main transmission line.

60 6. The invention as set forth in claim 5 wherein each of said branch lines includes means for changing the length of the transmission path through said branch lines by one-half wave length.

7. The invention as set forth in claim 5 wherein each of said branch lines includes an auxiliary line section one-half wave length long and means for short-circuiting said section.
